UNITED STATES PATENT OFFICE.

JOSEF REULEAUX, OF WILKINSBURG, PENNSYLVANIA.

GAS-PRODUCER.

No. 824,888.

Specification of Letters Patent.

Patented July 3, 1906.

Application filed October 8, 1895. Serial No. 281,863.

To all whom it may concern:

Be it known that I, JOSEF REULEAUX, of Wilkinsburg, in the county of Allegheny and State of Pennsylvania, have invented certain new and useful Improvements in Gas-
Producers; and I do hereby declare the following to be a full, clear, and exact description of the invention, such as will enable others skilled in the art to which it appertains to make and use the same.

The primary object of this invention is to provide simple and highly efficient means for insuring an increased air-supply to gas-producers, so as to thereby increase the capacity of ordinary producers as heretofore constructed and also to enable producers to be constructed on a larger scale than has heretofore been feasible.

A further object is to avoid any interference with the air-supply furnished by the ordinary distributor at the center of the producer, and at the same time have this additional supply enter the producer uniformly with that from the distributor.

The invention will be hereinafter fully set forth, and particularly pointed out in the claims.

In the accompanying drawings, Figure 1 is a vertical longitudinal sectional view of a producer equipped with my improvements. Figs. 2 and 3 are horizontal sectional views on lines 2 2 and 3 3, respectively, Fig. 1. Fig. 4 is a detail of a damper in section. Fig. 5 is a cross-section on line 5 5, Fig. 4.

I have shown my present improvements as applied to the well-known form of water-sealed producer. The ash-hopper 1 depends from a horizontally-disposed ring-like plate 2, supported by columns 3 of the lower portion of the producer-body 4, such hopper extending into the sealing-bottom 5, designed to contain water, as customary.

6 is the ordinary central air-distributer formed with a series of horizontal outlets for the air arranged one above another, the air being supplied through a blast-pipe 7, extending outwardly from the producer, preferably through the bottom 5. From the lower cylindrical portion 8 of the distributor extend four, more or less, hollow arms 9, which pass through the ash-hopper as well as the sides of the producer, being closed at their ends.

Directly above the ring-like plate 2 and parallel therewith, but spaced apart therefrom, is a second ring-like plate 12, formed on

its under side adjacent its edges with two series of lugs 13, which bear upon the upper face of plate 2. In this way a continuous air space or chamber is formed between the two ring-like plates. The inner circumference of this plate 12 is contiguous to the inclined portion of the producer. Air is supplied to the space between the upper and lower plates through openings 14, leading from the hollow arms 9, such openings being controlled by separate dampers 15, as shown in Figs. 2, 3, 4, and 5. It will be noted that the air supplied in this way will pass upwardly into the producer around or in close relation to the wall thereof, and also that the entrance of such air is at or about in line with the level of the lowermost blast from the central distributer. In consequence this additional air-supply in no way interferes with the work of the central distributer, but, on the contrary, adds greatly to the efficiency of the producer, since such additional supply will have to travel through as great a depth of fuel as any of the air supplied at the center.

The dampers 15 are of cylindrical formation, open each at its inner end and closed at its outer end, which end also serves to close the ends of the hollow arms 9. Each damper has a cut-out 16 in its cylindrical portion designed to coincide with the adjacent opening 14. Hence by turning these dampers axially through the agency of the operating-handles 17 the quantity of air admitted to the space between plates 2 and 12 may be readily controlled.

By means of my invention that part of the fuel-bed more or less remote from the center of the producer will be reached by the air, and the fuel close to the wall instead of remaining idle will contribute equally with the rest of the fuel in the production of gas. Furthermore, by introducing the additional air-supply at or about the level of the lowermost outlet from the central distributer both air-supplies will travel together uniformly and neither will interfere with the other.

It will be noted that the handles 17 stand parallel to the producer or at right angles to the dampers, and hence occupy but little room. The dampers being round gas-tight joints are insured, and in addition, as the ends of the valves serve to close the hollow arms, no extra lids or covers are necessary. By withdrawing the dampers access may be readily had to each arm for cleaning purposes.

2
I claim as my invention—

1. A gas-producer having in its body two spaced-apart ring-like plates forming an air space or chamber opening at its inner side into the producer, in combination with a central air-distributer, and means connecting the latter with said chamber, whereby air will be supplied to the producer at the center thereof and also at the side, said chamber opening into the producer about in line with the lowermost outlet from the distributer.
2. In a gas-producer, a central air-distributer having a depending portion, an air-supply space or chamber opening at its inner side into the producer at the side thereof, means connected with said depending portion for supplying air to the distributer, and hollow arms connecting said depending portion to said air space or chamber, for supplying air to the latter, the air therefrom entering the producer about in line with the lowermost outlet from the distributer.
3. A gas-producer having a horizontally-disposed ring-like plate, the ash-hopper depending therefrom, an upper ring-like plate, lugs spacing said plates apart, a central air-distributer, hollow arms leading from the latter and communicating with the space between said upper and lower plates at points near the side of the producer, and means for controlling such communication, as set forth.
4. The combination with the producer

having the continuous horizontal air-space, and the air-supply arms or conduits opening thereinto at or near their outer ends, of the 35 cylindrical dampers fitted in and closing the ends of said arms, and having cut-outs for coinciding with the openings into said air-space.

5. The combination with the producer 40 having the continuous horizontal air-space, and the air-supply arms or conduits opening thereinto at or near their outer ends, of the cylindrical dampers fitted in and closing the ends of said arms, and having cut-outs for 45 coinciding with the openings into said air-space, and handles for said dampers at right angles thereto.

6. The combination with the producer having the continuous horizontal air-space, 50 and the air-supply arms or conduits opening thereinto at or near their outer ends, of the cylindrical dampers fitted in said arms open at their inner ends and closed at their outer ends, said dampers having cut-outs in their 55 sides for coinciding with the openings into said air-space.

In testimony whereof I have signed this specification in the presence of two subscribing witnesses.

JOSEF REULEAUX.
